CLAIM

The ornamental design for a lingual transpalatal stabilizing orthodontic arch appliance, as shown and described.

DESCRIPTION

FIG. 1 is a perspective view of one embodiment of the lingual transpalatal stabilizing orthodontic arch appliance design of this invention, depicting the bottom, right side, and rear thereof;
FIG. 2 is a rear view thereof;
FIG. 3 is a bottom view thereof;
FIG. 4 is a left side elevational view thereof, with the right side being a mirror image;
FIG. 5 is a top plan view thereof; and,
FIG. 6 is a front elevational view thereof.

FIG. 1

FIG. 2

FIG. 4

FIG. 3

FIG. 5

FIG. 6
